ROOF CONSTRUCTION

Filed Nov. 16, 1935

UNITED STATES PATENT OFFICE

2,070,648

ROOF CONSTRUCTION

Raymond M. Calkins, Deerfield, and James W. Swank, Chicago, Ill.

Application November 16, 1935, Serial No. 50,076

10 Claims. (Cl. 108—13)

Our invention relates to roof construction of the type involving panels of sheet metal or other suitable material, and it is the object of our invention to provide a new and improved form and arrangement of parts by the use of which an improved roof structure may be produced. It is one of the objects of our invention to provide an improved arrangement of panels made of sheet material and provided along their edge portions with improved interfitting parts adapted to hold the several panels in overlapping arrangement.

It is another object of our invention to provide an improved arrangement of insulating and reinforcing means for a roof panel of this type whereby the roof in its finished form is effective for preventing the passage of heat therethrough and is of such structural strength as to withstand the pressures likely to be applied thereto by the wind or by a load of snow, and whereby the separate panels as they come from the factory are of such strength as to keep their shape in shipment so as to be capable of fitting readily into interlocking engagement with the adjacent panels for the formation of the roof.

It is another object of our invention to provide an improved form of ridge member adapted to have interfitting engagement with the uppermost tiers of panels at opposite sides. It is another object of our invention to provide an improved form of eaves member also adapted to have interfitting engagement with the adjacent panels.

It is one of the objects of our invention to provide an improved arrangement of supporting and attaching means for holding the panels and other parts firmly in position.

It is another object of our invention to improve roof construction of this type in sundry details hereinafter pointed out. The preferred means by which we have accomplished our several objects are illustrated in the drawing and are hereinafter specifically described. That which we believe to be new and desire to cover by Letters Patent is set forth in the claims.

In the drawing,—

Fig. 1 is a vertical cross sectional view through a roof embodying our invention, parts of the structure being broken away for clearness of illustration;

Fig. 2 is a vertical section through one of our improved roof panels;

Fig. 3 is a cross sectional view through two adjacent panels showing the end construction of the panels; and

Fig. 4 is a vertical cross sectional view through our improved ridge member.

Referring now to the several figures of the drawing, in which corresponding parts are indicated by the same reference characters, 10 indicates the side wall of a building having a top plate 11 secured thereon longitudinally thereof. 5 The wall 10 as shown in our drawing is of the type disclosed and claimed by our prior application Serial No. 758,843, filed December 22, 1934, the top plate 11 being secured in position upon the wall by means of hook bolts 12 of the type 10 disclosed by said application. The framework of the roof comprises a plurality of rafters 13 which are shown in the form of channel bars on edge, the rafters being seated at their lower ends against vertically disposed plate portions 14. In- 15 wardly directed plate portions 15 extend underneath the ends of the rafters, tongues 16 being cut from the plate 15 at intervals therealong and bent upwardly into engagement with the rafters and secured in position by means of bolts 17. 20 The oppositely disposed rafters 13 at opposite sides of the building are rigidly connected by tie members 18 of any approved type.

At the lower edge of the roof at each side of the building, we have provided an eaves member 19 of sheet metal supported at its upper edge by a straight inwardly directed flange portion 20, upon the inner edge of which is formed a box-like structure comprising flange portions 21 and 22 formed integrally with the flange 20. The 30 flange 20 stands in engagement with an angle bar 23 mounted in crossed relationship to the rafters 13 at their lower ends, being held in position by means of bolts 24. At a point spaced downwardly a substantial distance below the 35 supporting flange 20, the sheet metal is turned downwardly to provide a facing member 25 and thence inwardly so as to provide a horizontal panel portion 26 and then downwardly to provide a flange 27 which is rigidly secured by any suit- 40 able means to the outer face of the wall 10.

The principal portion of the roof is made up of a series of similar panels 28 of sheet metal each having an inwardly directed straight flange 20 and integrally formed flanges 21 and 22 in 45 box arrangement as is described above in connection with the eaves member 19. At their lower edges, each of the roof panels 28 is bent inwardly and backwardly so as to provide a channel 29, connected with which there is a straight 50 inwardly directed supporting flange 30 having a box-like structure formed on its inner edge comprising flange portions 31, 32 and 33, as is best seen by reference to Fig. 2. The box-like structure at the lower edge of the lowest roof panel 55

28 is adapted to fit snugly within the box-like structure formed at the upper edge of the eaves member 19, and the box-like structure at the upper edge of each of the roof panels 28 is 5 adapted to receive snugly therein the box-like structure formed at the lower edge of the next higher panel 28, the roof being formed of a series of interfitted panels 28 each of which overlaps the panel member next below. The interfitted 10 box-like structures are secured to the rafters 13 by means of hook bolts 34 which are tightened against the edges of the flanges 22 and against the top faces of the flanges 33, such flanges 33 being distorted slightly by the pressure applied 15 through the hook bolts so as to hold the flanges 33 firmly against longitudinal movement, the parts being thus held very strongly in position.

For supporting the roof panels 28 in their operative position as described, we provide shelf 20 angles 35 secured in position across the rafters 25 angles 35 secured in position across the rafters by means of bolts 36 in position to engage the bottom faces of the supporting flanges 20.

At the angle of the roof, we have provided an 25 improved ridge member 37 also formed of sheet metal bent along its central line to provide panels 38 and 39 at opposite sides. Each of said panels is provided with a channel portion 40 at its lower edge from which inwardly extending straight flange portions 30 extend having inside box structures formed thereon as above described in connection with the panels 28.

For insulating the roof and for strengthening the construction, we have provided rigid insulation board members 41 upon the inner faces 35 of the panels 28, 38 and 39, layers 42 of asphalt emulsion being interposed between the insulation boards and the faces of the panels. As is best shown in Fig. 2, the boards 41 and the layers of emulsion 42 are of such thickness as to fit snugly 40 within the channels 29—40 of the members whereby the channels are protected positively against collapse. The upper edges of the insulation boards are secured in position by means of bolts 43 extending through the boards and 45 through the sheet metal of the panel. By the use of the rigid insulation boards 41 secured in position both by the layer of asphalt emulsion and also by the mechanical means as described, the panel members are very greatly strengthened 50 so as to be enabled to keep their shape during handling and shipment from the factory so as to fit without difficulty in the desired interlocking engagement with each other when applied in operative position upon the framework. Similar 55 rigid insulation board members 41a are secured by layers 42 of asphalt emulsion and bolts 43 on the inside faces of the eaves panels between the supporting flanges and the facing portions 25 of said panels.

60 By the arrangement of the supporting flanges 20 and 30 in engagement with each other and both extending straight from the panel to be supported to the face of the rafter 13, the construction is given such strength as to enable it to 65 withstand the pressure applied thereon by the wind or by a load of snow, particularly when such structure is reinforced by the shelf angles 23 and 35 as above described.

At their end portions, the several panels are 70 connected preferably in the manner shown in Fig. 3, comprising inwardly turned flange portions 44 which are arranged in spaced relation to each other at the outer faces of the members but which stand in snug engagement with each other at an inwardly spaced point. By this ar-

angement, a channel is provided into which a calking member 45 is inserted for effecting the desired tight joint between the parts.

While we prefer to employ the form and arrangement of parts as shown in our drawing and 5 as above described, it is to be understood that our invention is not limited thereto but that changes may well be made in the form shown without departing from the spirit of our invention.

We claim:—

1. A roof construction comprising in combination a plurality of spaced rafters, a series of panels of sheet metal secured in crossed relationship to said rafters by inwardly turned straight flange portions formed integrally with 15 the panels at their top and bottom edge portions, and bars secured in crossed relationship to said rafters below the securing flange portions of said panels in position to brace said flanges for holding the panels firmly in operative position. 20

2. A roof construction comprising in combination a plurality of spaced rafters, a series of panels of sheet metal secured in crossed relationship to said rafters by inwardly turned straight 25 flange portions formed integrally with the panels at their top and bottom edge portions, the flange at the lower edge portion of each of said panels being offset upwardly from the extreme edge of 30 the panel by a channel arrangement for permitting each panel to overlap the adjacent lower panel, means for bracing said channel portions for preventing the collapse of the channels, and angle bars secured in crossed relationship to said 35 rafters below the securing flange portions of the panels in position to brace said flanges for holding the panels firmly in operative position.

3. A roof construction comprising in combination a plurality of spaced rafters, a series of panels of sheet metal secured in crossed relationship 40 to said rafters by inwardly turned straight flange portions formed integrally with the panels at their top and bottom edge portions, the flange at the lower edge portion of each of said panels being offset upwardly from the extreme edge of 45 the panel by a channel arrangement for permitting each panel to overlap the adjacent lower panel, and rigid board insulation members secured on the bottom faces of said panels extending from the securing flanges at the upper edges 50 of the panels and snugly filling said channel portions serving to prevent the collapse of the channels.

4. A roof construction comprising in combination a plurality of spaced rafters, a series of 55 panels of sheet metal secured in crossed relationship to said rafters by inwardly turned straight flange portions formed integrally with the panels at their top and bottom edge portions, the flange at the lower edge portion of 60 each of said panels being offset upwardly from the extreme edge of the panel by a channel arrangement for permitting each panel to overlap the adjacent lower panel, rigid board insulation members secured on the bottom faces of said 65 panels extending from the securing flanges at the upper edges of the panels and snugly filling said channel portions serving to prevent the collapse of the channels, and bars secured in crossed relationship to said rafters below the securing 70 flange portions of said panels each in position to brace the upper flange of one panel and the lower flange of the next higher panel for holding the panels firmly in operative position.

5. A roof construction comprising in combi- 75

- nation a plurality of spaced rafters, a series of panels of sheet metal arranged in crossed relationship to said rafters and each having an inwardly turned straight flange portion formed integrally therewith at both its top and its bottom edge portions, the flange at the lower edge portion of each of said panels being offset upwardly from the extreme edge of the panel by a channel arrangement for permitting each panel to overlap the adjacent lower panel, interengaging box-like structures formed integrally with said inwardly turned flange portions, means for securing said box-like structures rigidly in position on said rafters, and means for bracing said channel portions for preventing the collapse of the channels.
6. A roof construction comprising in combination a plurality of spaced rafters, a series of panels of sheet metal arranged in crossed relationship to said rafters and each having an inwardly turned straight flange portion formed integrally therewith at both its top and its bottom edge portions, the flange at the lower edge portion of each of said panels being offset upwardly from the extreme edge of the panel by a channel arrangement for permitting each panel to overlap the adjacent lower panel, interengaging box-like structures formed integrally with said inwardly turned flange portions, hook bolts extending through portions of the rafters and engaging said box-like structures for securing the panels rigidly in position on the rafters, and means for bracing said channel portions for preventing the collapse of the channels.
7. A roof construction comprising in combination a plurality of spaced rafters, a series of panels of sheet metal arranged in crossed relationship to said rafters and each having an inwardly turned straight flange portion formed integrally therewith at both its top and its bottom edge portions, the flange at the lower edge portion of each of said panels being offset upwardly from the extreme edge of the panel by a channel arrangement for permitting each panel to overlap the adjacent lower panel, interengaging box-like structures formed integrally with said inwardly turned flange portions, hook bolts extending through portions of the rafters and engaging said box-like structures for securing the panels rigidly in position on the rafters, bars secured in crossed relationship to said rafters below said securing flange portions in position to brace said flanges for holding the panels firmly in operative position, and rigid board insulation members secured on the bottom faces of said panels extending from the securing flanges at the upper edges of the panels and snugly filling the channels at the lower edge portions of the panels serving to prevent the collapse of the channels.

8. A roof construction comprising in combination a plurality of rafters rising in spaced relation from a supporting structure to be covered, a bar secured in crossed relationship to said rafters at their lower end portions, an eaves panel of sheet metal having an inwardly directed straight flange portion in engagement with said bar so as to be supported thereby, a box-like structure formed integrally with said flange portion and engaging said rafters in position to receive therein an interfitting box-like structure of an adjacent panel, and hook bolts extending through portions of the rafters and engaging said box-like structure for holding said eaves panel firmly in position.

9. A roof construction comprising in combination a plurality of rafters in spaced relation at opposite sides of the roof structure, bars secured in crossed relationship to said rafters at opposite sides of the structure near the upper ends of the rafters, a ridge member formed of sheet metal bent to form panels in angular relation to each other and having inwardly directed straight flange portions at its opposite edges both offset upwardly from the extreme lower edges of the member by a channel arrangement at each side and having box-like structures formed integrally with said flange portions in position to enter interfitting box-like structures of adjacent panels arranged in engagement with said cross bars, and means for securing said box-like structures of said ridge member rigidly in position on said rafters.

10. A roof construction comprising in combination a plurality of rafters in spaced relation at opposite sides of the roof structure, bars secured in crossed relationship to said rafters at opposite sides of the structure near the upper ends of the rafters, a ridge member formed of sheet metal bent to form panels in angular relation to each other and having inwardly directed straight flange portions at its opposite edges both offset upwardly from the extreme lower edges of the member by a channel arrangement at each side and having box-like structures formed integrally with said flange portions in position to enter interfitting box-like structures of adjacent panels arranged in engagement with said cross bars, rigid board insulation members secured on the inner faces of said panels and extending into said channels serving to prevent the collapse of the channels, and hook bolts extending through portions of the rafters and engaging said box-like structures for holding said ridge member firmly in position.

RAYMOND M. CALKINS.
